MAGNETO

Curt F. Reis, Chicago, Ill., assignor to Superior Parts Manufacturing Company, New York, N. Y., a corporation of New York

Application January 10, 1938, Serial No. 184,208

1 Claim. (Cl. 171—209)

This invention relates to magnetos and more particularly to improvements in the structure and assembly arrangement of certain of the magneto parts, whereby to provide a compact and efficient magneto for ignition purposes and the like.

Among the objects of the invention are the provision of a housing for the operating elements of the magneto, the housing including a removable frame member forming an extension for the housing, and a cover therefor, each supporting certain of the magneto parts; the provision of a removable housing extension member formed to provide a seat for a bearing assembly supporting one end of the magneto rotor, and adapted for the support of the distributor mechanism, breaker assembly and distributor brush assembly, and the provision of a combined current collector and distributor assembly.

Other objects and advantages will appear from the following description, as read in connection with the accompanying drawings, in which:

Fig. 1 is a longitudinal sectional elevation of the improved magneto assembly; Fig. 2 is a transverse section thereof taken along line 2—2 in Fig. 1, illustrating the breaker mechanism, and Figs. 3 and 4 are transverse sections of the magneto taken respectively, along lines 3—3 and 4—4 in Fig. 1, the views illustrating respectively, elements of the current collector mechanism and the brush and distributor assembly.

Referring to the drawings by suitable characters of reference, 10 indicates generally a magneto embodying the improvements of the invention.

The magneto which is adapted particularly for engine ignition purposes, includes a housing 11 formed of cast metal, preferably an aluminum alloy, but which may be formed of any suitable material, as desired. Supported by 40 the housing is a stator structure indicated generally at 12 (Fig. 2), which includes a high tension generating winding assembly 14 (Figs. 1 and 2). A magneto rotor 15 functionally cooperates with stator 12, the type of rotor contemplated to be employed as a preference in the present assembly, constituting of itself, the subject matter of my copending application, Serial No. 175,576, filed November 20, 1937. Rotor 15 is mounted on a shaft 16 which has one end 18

50 journaled in a bearing assembly 19 carried by an end wall 20 of the housing 11. The shaft end 18 is extended outwardly beyond the wall 20, for coupling to a driving element of the engine (not shown) with which the magneto is associated.

55 As shown by Fig. 1, the magneto shaft driving coupling is comprised of an impulse type of coupling which may be of any well known form. The impulse coupling illustrated, includes a disc 22 sleeved upon a tapered portion 23 of the magneto shaft end 18 and locked thereon by a lock

nut 24. Other operating elements of the coupling appearing in Fig. 1, include an engine driven element 26 and a torsion spring 27 the ends of which (not shown) are connected, one to the element 26 and the other to the disc 22. As the impulse coupling forms no part of the invention, a further description thereof is deemed unnecessary.

Forming a continuation of housing 11 at the end thereof opposite wall 20, is a frame member 28 preferably formed of an aluminum alloy casting and provided with a circumferential flange 30 through which it is secured to housing 11, as by screws 31 (Fig. 2). An upstanding partition or wall member 32 within the frame 28 is formed to provide, in cooperation with a recess 34 in the lower portion 35 of flange 30, a chamber or pocket 36 for the reception of a bearing assembly 38. The bearing 38 which may be of the ball-race type as shown, serves to support the magneto rotor shaft end portion 39, and thus to complete the rotational mounting of the rotor.

A stub shaft 40 which serves as an operating support for a magneto distributor rotor and breaker cam mechanism later to be described, is 25 journaled by preference in a ball-race type of bearing 42 which is seated in a recess 43 formed in the upper end portion of wall 32. A gear 44 keyed or otherwise secured to one end of the stub shaft, operatively engages a pinion 46 on the end 30 of the magneto rotor shaft 16, the gear and pinion serving to drive the stub shaft, through rotation of the magneto rotor shaft 16 by the engine.

To the opposite end 50 of the stub shaft is secured a flanged disc 51 formed of a suitable insulating material, such as hard rubber, fiber or Bakelite. Embedded in a circumferential surface portion of the disc is a metallic contact segment 52, formed of copper or other good conducting material. Formed by preference as an integral part of segment 52, is a conducting element or arm 54 also embedded in the disc element, the arm being extended through one of the disc flanges and thence radially inwardly to the axis 45 of the disc (Figs. 1 and 4). Current generated in winding 14 is conducted to the segment 52 through its arm 54 in a manner now to be described.

Removably secured to the open end of the 50 frame 28 is a plate or cover element 55 formed by preference of an aluminum alloy, the cover having secured thereto on its inner side, a bracket 56 formed of a suitable insulating material, such as fiber or Bakelite, the assembly of the bracket 55 to the cover being effected by suitable screws 58. Carried by the bracket is a metallic block 59 which supports a metallic conductor bar 60, the bar being extended inwardly of frame 28 for electrical contact with a spring contact 62 on winding 60

- 14, the spring contact being electrically connected to the high tension terminal (not shown) of the winding. Also carried by the block 59 as by the screw 63, is a resilient, metallic finger element 5 64 which supports at its free end, a contact point or ball 66. The spring finger 64 is arranged so that its contact ball 66 is in electrical engagement with the inner end of the arm 54 (Fig. 1), this portion of the arm being located at the axis of 10 the disc 51, so that contact is maintained between ball 66 and arm 54 throughout disc rotation. It is to be noted as a feature of the invention, that the free end of conductor bar 60 and the ball contact 66 make contact respectively, with the 15 high tension contact 62 and arm 54 only through frictional engagement therewith, so that ready disengagement therebetween may be effected upon removal of the cover 55 which supports the bar 60 and finger contact 64.
- 20 The bar 60, block 59, finger 64 and its contact ball 66, and element 54 serve to conduct high tension current from the magneto generating winding 14 to the contact segment 52 on disc 51. Distribution of the high tension current to the 25 engine ignition elements, such as spark plugs (not shown), is made by the segment 52 through angularly spaced brushes 67 arranged for frictional engagement with the peripheral surface of disc 51 and in the path of the segment 52. Thus 30 the disc 51 and its contact segment 52 function as a current distributor rotor. Although two brushes are illustrated, adapting the magneto to a two-cylinder engine, any number of brushes may be employed in properly spaced relation, to 35 accommodate engines having more than two cylinders. The magneto and its two-brush distributor as shown, may be used also on single cylinder engines, through the utilization of but one of the brushes.
- 40 In the example shown, each brush 67 is carried by a brush holder 68 which is mounted upon or formed as an integral part of the frame member 28. A suitable high tension conductor 70 leading from each brush and its holder, connects the 45 brush with an engine spark plug (not shown). The brushes and their holders are illustrated as located in the lower portion of the frame 28 and angularly spaced by substantially 90 degrees.
- From the foregoing, it will be observed that 50 the related elements 60, 59, 64, 66, 54, 52 serve to collect high tension current and to distribute such current to the engine ignition means, through the brushes 67. Thus a greatly simplified and substantially unitary mechanism is provided for the purpose noted.
- 55 The breaker or timer mechanism for the grounded side of the high tension magneto winding 14 is carried by the frame 28, along with the collector and distributor mechanism above described. The breaker includes a projection 71 on the wall 32, which serves as a support for an adjustable contact 72, this contact being connected to the terminal 74 of winding 14 by a lead 75. Cooperating with contact 72 is a contact 76 carried on one end of an arm 78, the arm being pivoted at 79 to the wall 32. A spring 80 attached to the arm and bearing against a strengthening boss 82 for the wall 32, serves to urge the arm 78 about its pivot in a direction to 60 effect engagement of contact 76 with contact 72. Actuation of the arm 78 is effected by a cam 83 formed by preference, as an integral part of the stub shaft 40, the position of the cam being be-

tween the shaft bearing and the disc 51 (Fig. 1). The arm 78 carries a finger or cam follower 84 formed of a suitable insulating material, such as fiber, and located so that its free end bears against the cam face. Contact of the follower with the cam is maintained by the spring 80 acting on the arm 78. A conductor 86 extending from the arm 78 is connected by screw 87, to the boss 82, thus providing the ground return for the ignition circuit.

10 The proper timing of breaker operation is attained through the particular surface contour of the cam 83 and the operating ratio of gears 44 and 46, these factors being predetermined for a given engine with which the magneto is to be 15 utilized.

20 From the foregoing description, it will appear now that the breaker assembly, current collector and distributor mechanism and one of the magneto rotor bearings are all carried by the frame 28 and its cover 55. By disconnecting the frame 28 from the magneto housing 11, all of the above parts are removed therewith without materially disturbing the remainder of the magneto assembly. Thus there is provided an improved magneto assembly which may be quickly and easily disassembled, as for inspection or repair purposes. Further, the assembly is comprised of but few parts arranged in a highly compact, but 25 readily accessible manner.

30 While the above description relates to a single, preferred embodiment of the invention, it is to be understood that modifications in the parts thereof or alterations in location of the parts may be effected without departing from the spirit and 35 scope of the invention, as defined by the appended claim.

I claim:

40 In a magneto assembly, a frame structure of unitary cast construction and being of hooded type, open at the end opposite the driving connection of the magneto, a tubular element removably mounted on said frame adjacent the open end thereof, ignition terminals carried in spaced relation by the tubular element, a magneto shaft 45 and a magneto rotor supported thereby, a wall member projecting inwardly of the tubular element, bearing means carried by said wall, rotatably receiving one end of the magneto rotor shaft, a distributor shaft journalled in said wall, 50 gearing connecting the magneto rotor and distributor shafts, a breaker assembly carried entirely by the wall member, a distributor rotor carried by one end of the distributor shaft, a contact element carried by the distributor rotor, 55 a breaker cam on the distributor shaft between the distributor rotor and said wall member, an end closure plate for the tubular element serving therewith to complete the enclosure provided by the frame for the internal elements of the magneto, a high tension current generating winding supported in said frame and operatively associated with said magneto rotor, a relatively rigid conductor element carried by and projected inwardly of the closure plate, and adapted for 60 abutting contact with an opposed conductor element of said generating winding, and a relatively rigid yet somewhat resilient distributor supply conductor electrically connected to the conductor aforesaid and mounted internally of the closure 65 plate in a manner to engage a portion of the contact on said distributor rotor.

70 CURT F. REIS.
